Specification for Design.

Patented Nov. 21, 1916.

Application filed August 19, 1916. Serial No. 115,907. Term of patent 14 years.

To all whom it may concern:

Be it known that I, JOHN F. KELLY, a citizen of the United States, residing at Trenton, in the county of Mercer and State of New Jersey, have invented a new, original, and ornamental Design for a Lavatory, of which the following is a specification, reference being had to the accompanying drawings, forming part thereof, in which—

Figure 1 is a plan view of a lavatory showing my new design. Fig. 2 is a front

elevation of the same and Fig. 3 is a transverse cross-section taken on the line 3—3 Fig. 1.

I claim:

The ornamental design for a lavatory as shown.

JOHN F. KELLY.
